(57) **CLAIM**

The ornamental design for a set of labels for vehicle battery, as shown and described.

DESCRIPTION

FIG. 1 is a front perspective view of the present new design for a set of labels for vehicle battery applied to an exemplary vehicle battery which is illustrated in dashed lines and forms no part of the claimed design; and,

FIG. 2 is a front view thereof illustrating how the set of labels for vehicle battery appears in isolation and not applied to an article.

The set of labels for vehicle battery is embraced in brackets to show the relationship between each label in the set of labels.
